CLAIM

The ornamental design for a touch sensor drum keyboard, as shown.

DESCRIPTION

FIG. 1 is a front view of a touch sensor drum keyboard showing my new design;

FIG. 2 is a rear view thereof;

FIG. 3 is a right view thereof;

FIG. 4 is a left view thereof;

FIG. 5 is a top view thereof;

FIG. 6 is a bottom view thereof;

FIG. 7 is a top front perspective view thereof;

FIG. 8 is a top rear perspective view thereof;

FIG. 9 is a top right front perspective view thereof; and,

FIG. 10 is a bottom right front perspective view thereof.
